UNITED STATES PATENT OFFICE.

DAVID SPALDING, OF LONEROCK, OREGON.

FENCE-WIRE CLAMP.

Application filed June 24, 1921. Serial No. 480,106.

To all whom it may concern:

Be it known that I, DAVID SPALDING, a citizen of Great Britain, residing at Lonerock, in the county of Gilliam, State of Oregon, U. S. A., have invented a new and useful Fence-Wire Clamp; and I do hereby declare the following to be a full, clear, and exact description of the invention, such as will enable others skilled in the art to which

10 it appertains to make and use the same.

The invention relates to fence wire clamps and has for its object to provide a device of this character wherein the fence wire will be held in such a manner that all of its longitudinal disposed strands will be securely held between hingedly connected members having a metallic rod therein and a groove registering with said rod, said rod and groove forming means for bending the longitudinal strands during a clamping operation.

A further object is to provide a centrally disposed clamp for holding the hinged members against bowing outwardly during a wire clamping operation, thereby insuring a uniform clamping action.

A further object is to form the clamping members from wood or a light material or to imbed in one face thereof a metallic rod, 30 one side of which metallic rod cooperates with a groove in the opposite hinged member for bending the wires of the wire fence mesh work.

With the above and other objects in view 35 the invention resides in the combination and arrangement of parts as hereinafter set forth, shown in the drawings, described and claimed, it being understood that changes in the precise embodiment of the invention may 40 be made within the scope of what is claimed without departing from the spirit of the invention.

In the drawings:—

Figure 1 is a side elevation of the wire 45 clamp.

Figure 2 is a front elevation of the wire clamp.

Figure 3 is a perspective view of the wire 50 clamp showing the hinged members partially open.

Figure 4 is a detail view of the means for pivoting the securing bolt of the clamp.

Figure 5 is a top plan view of a clamp for holding the hinged clamp members against 55 spring outwardly during a clamping operation.

Referring to the drawings, the numerals 1 and 2 designate elongated clamping members, which members are preferably rectangular shaped in horizontal cross section and 60 provided with registering semi-circular grooves 3 and 4, said grooves extending longitudinally of the inner faces of the clamping members 1 and 2. Disposed within the clamping member 2 and in the groove 65 4 thereof is a longitudinally disposed metallic rod 5, which rod is provided with transversely disposed bars 6 disposed in recesses 7 of the clamping member 2. When the clamping members 1 and 2 are forced together after the wire fencing 8 is placed therebetween and the members 1 and 2 closed on the hinging point 9, said bar 5 will bend the longitudinally disposed strands 10 of the fencing 8 when said bar 5 is forced into the 70 groove 3. By bending the strands 10 it will be seen that they will be held against slipping when chains 11 are connected to the transversely disposed bars 6 by connecting the chains to the eyes 12. Pivotally secured 75 on a cross bar 13 carried on the outer face of the upper end of the clamping member 2 is a threaded bolt 14, which bolt extends through registering slots 15 in the free ends of the clamping members 1 and 2 and is provided with a lever 16, by means of which lever the clamping members 1 and 2 may be securely clamped together. Transversely disposed bars 6 are connected to the round 80 rod 5 by means of rivets 16, therefore it will 85 be seen that when a pull is imparted on the chains 11 that the strain will be equally distributed throughout the clamp, and at the same time so distributed that the main spring falls on the longitudinally disposed rod 5, 90 which rod not only forms means for placing bends in the longitudinally disposed wires 10 but also forms means for bracing longitudinally the clamp as a whole during a 95 clamping operation. It has been found that 100 a clamping action must be positive throughout the length of the clamp if slipping is to be prevented. To accomplish this result an auxiliary clamp 17 is provided, which clamp is adapted to be centrally disposed on the 105 members 1 and 2 when they are in closed position for preventing outward springing of said members during a clamping operation. By providing the clamping member 17 the size of the main clamp may be reduced to a 110 minimum and all of the best results obtainable in an extremely large clamp which

would be unwieldy is obtainable in a lighter constructed clamp.

From the above it will be seen that a wire clamp is provided which is simple in construction and one wherein the parts have been reduced to a minimum.

The transversely disposed plates 6 have their ends 18 provided with lugs 19, which lugs when the clamping members 1 and 2 are brought together overlie the side of the clamping member 1 and form means for additionally holding the clamping member 1 against movement during a wire fence stretching operation.

15 The invention having been set forth what is claimed as new and useful is:—

A wire fence stretching device comprising a pair of hingedly connected elongated rectangular shaped clamping members, the adjacent faces of said members being provided with longitudinally disposed semi-circular grooves in registration with each other, one

of said grooves having disposed therein a metallic rod, transversely disposed bars carried by said metallic rod and imbedded in one of the clamping members, rivets passing through the rod, the transversely disposed bars and the clamping member for holding said parts together, the ends of the transversely disposed bars at one side of the member on which they are disposed being provided with lugs for overlying the side of the adjacent clamping member, and means whereby members may be connected to one end of the transversely disposed bars for imparting a pull on the clamping device as a whole.

In testimony whereof I have signed my name to this specification in the presence of two subscribing witnesses,

DAVID SPALDING.
